CHARLES WALES, OF NEW HAVEN, CONNECTICUT, ASSIGNOR TO THE WHITE ADDING MACHINE COMPANY, OF NEW HAVEN, CONNECTICUT, A CORPORATION OF CONNECTICUT.

DASH-POT.

1,115,628.

Specification of Letters Patent.

Patented Nov. 3, 1914.

Application filed April 19, 1913. Serial No. 762,434.

To all whom it may concern:

Be it known that I, CHARLES WALES, a citizen of the United States, residing at New Haven, in the county of New Haven and State of Connecticut, have invented a new and useful Improvement in Dash-Pots, of which the following is a specification, reference being had to the accompanying drawing.

10 My improvement relates to such dash-pots as are used in various mechanical apparatus for retarding motion of some part which is driven in one direction by gravity, manually or by mechanical power, the purpose being to insure such movement within a desired range of time, or to prevent shock. The object of my improvement is, by means other than piston rod packing, to provide a dash-pot which may turn from the 20 upright position without discharging the liquid used as a retarding medium, in order that the dash-pot may be adapted for use in such forms of apparatus as are portable and therefore liable to be turned from the 25 upright position.

In the accompanying drawings, Figure 1 is an upright sectional elevation of a dash-pot embodying my improvement; Fig. 2 is a longitudinal section of the same dash-pot turned lengthwise into the horizontal position; Fig. 3 is a section on the line 3-3, of Fig. 1; Fig. 4 is a section on the line, 4-4, of Fig. 2.

The apparatus comprises a chamber consisting of a lower section, A, and an upper section, B, said two sections being hermetically joined to each other axially in line with each other. In the particular form shown in the drawings, the upper section, 35 B, has at its lower and upper end an outward directed flange, C, extending over the rim, D, of the section, A. Screws E, extend through said flange into the section, A, to bind said sections together. To aid in making a liquid-tight joint, a suitable washer, F, may be interposed between said flange and said rim. And the internal diameter of the section, B, is preferably made less than the 40 internal diameter of the section, A, in order that the piston (hereinafter described) may be confined within the lower section and thereby have its upward movement limited. In the head or top wall, G, of the upper section, B, is a central aperture, H. In said 45 aperture is rigidly secured the upper end of

a tube, I, the lower end of said tube reaching, in the form shown in the drawings, a little more than half way through the length of the upper section, B. This tube is concentric to the axis of the chamber composed of the sections, A and B. A piston stem or "falling rod", J, extends loosely downward through the tube, I, into the lower chamber section, A, and there supports the piston, K. Three relatively narrow ribs, R, are formed on the interior of the tube at the outer end of the latter and parallel to the stem, J, to form a limited contact area between said stem and said tube. A sleeve, M, surrounds the stem, J, and has at its lower end a hub, 50 N, fitted to the stem and secured thereto by a cross pin, O. The portion of said sleeve above said hub has an interior diameter a little larger than the exterior diameter of the tube, I, and said sleeve is long enough 55 to surround the lower portion of said tube.

From the foregoing it will be seen that provision is made for the freest movement of said stem through said tube, and the liquid might pass between said tube and said 60 stem, if said liquid were properly directed for such result. But this is substantially avoided. As is usual, provision is made for the passing of the liquid around the piston (when the apparatus is in the upright position) to permit the retarded downward movement of the piston from its upper position. The quantity of the liquid is sufficient to fill the chamber almost to the rim of the lower section, A, as, for example, to 65 the dotted lines, L, when the chamber is in the upright position. When during transportation or storage the entire device is turned into the horizontal position, the liquid will extend into both sections of the chamber below the level of the tube, I, and sleeve, M, as indicated by Fig. 2. And when the device is turned still further, so as to invert it, the liquid will occupy what is then the lower portion of the chamber, around the 70 tube, I. The length of said tube must be sufficient to extend above the upper surface of the liquid when the device is thus inverted.

In practice I have found that even without the sleeve M, such a dash-pot is, to a considerable degree, effective, for it may be freely turned into all positions without any real flow of the liquid therefrom, there being, at the most, a discharge of only a few 75

drops of the liquid through the tube, I, this being the result of oil splashing against the stem, J, and creeping along the latter when the apparatus is so turned as to bring the 5 inner end of the stem higher than its outer end. The sleeve, M, serves as a mask or apron for protecting the portion of the stem immediately below the tube, I, from oil which is splashed as above described. 10 The oil splashes against said sleeve and creeps along the latter and falls from the outer end thereof without reaching the stem.

For the assemblage of the parts, the piston stem bearing the sleeve, M, and piston, 15 K, is put into position with reference to the upper chamber section, B. Then the lower chamber section, A, is applied to said upper section by means of the screws, E, extending through the flange, C, of the upper section, 20 B. For repair or renewal of the piston, or replenishing the liquid, said screws are withdrawn, and the section, B, lifted away from the section, A.

I claim as my invention:

- 25 1. In a liquid dash pot the combination of a chamber, a piston therein, a liquid in which said piston moves when the dash pot is in operation, a fixed tube extending downward into said chamber and having a surface exposed to the liquid contents of said chamber, and forming with the walls of said chamber a pocket for said liquid contents, and a piston stem extending through said tube and connected to said piston head.
- 30 2. In a liquid dash pot the combination of a chamber, a piston therein, a liquid in which said piston moves when the dash pot is in operation, a fixed tube extending downward into said chamber and having a surface exposed to the liquid contents of said chamber and forming with the walls of said chamber a pocket for said liquid contents, and a piston stem extending through said tube and connected to said piston head.
- 35 3. In a liquid dash pot the combination of a chamber, a piston therein, a liquid in which said piston moves when the dash pot is in operation, a fixed tube extending downward into said chamber and having a surface exposed to the liquid contents of said chamber and forming with the walls of said chamber a pocket for said liquid contents, and a piston stem extending through said tube and connected to said piston head, said tube extending into said chamber for a distance as great as the throw of said piston.
- 40 4. In a liquid dash pot the combination of a chamber, a piston therein, a liquid in which said piston moves when the dash pot is in operation, a fixed tube extending downward into said chamber and having a surface exposed to the liquid contents of said chamber and forming with the walls of said chamber a pocket for said liquid contents, a piston stem extending through said tube and connected to said piston head and a sleeve carried by said stem and loosely surrounding the lower end only of said tube when said piston is in depressed position, the other portion of said tube being then exposed to the fluid in said chamber.
- 45 5. In a liquid dash pot the combination of a chamber, a piston therein, a liquid in which said piston moves when the dash pot is in operation, a fixed tube extending downward into said chamber and having a surface exposed to the liquid contents of said chamber and forming with the walls of said chamber a pocket for said liquid contents, a piston stem extending through said tube and connected to said piston head, said tube extending into said chamber for a distance as great as the throw of said piston.
- 50 6. In a liquid dash pot the combination of a chamber, a piston therein, a liquid in which said piston moves when the dash pot is in operation, a fixed tube extending downward into said chamber and having a surface exposed to the liquid contents of said chamber and forming with the walls of said chamber a pocket for said liquid contents, a piston stem extending through said tube and connected to said piston head and a sleeve carried by said stem and loosely surrounding the lower end only of said tube when said piston is in depressed position, the other portion of said tube being then exposed to the fluid in said chamber, there being an air passage from the outside to the inside of said chamber bounded on one side by the stem of said piston.
- 55

4. In a liquid dash pot the combination of 60 a chamber, a piston therein, a liquid in which said piston moves when the dash pot is in operation, a fixed tube extending downward into said chamber and having a surface exposed to the liquid contents of said chamber 65 and forming with the walls of said chamber a pocket for said liquid contents, a piston stem extending through said tube and connected to said piston head and a sleeve carried by said stem and loosely surrounding 70 the lower end only of said tube when said piston is in depressed position, the other portion of said tube being then exposed to the fluid in said chamber.

5. In a liquid dash pot the combination of 75 a chamber, a piston therein, a liquid in which said piston moves when the dash pot is in operation, a fixed tube extending downward into said chamber and having a surface exposed to the liquid contents of said chamber 80 and forming with the walls of said chamber a pocket for said liquid contents, a piston stem extending through said tube and connected to said piston head, said tube extending into said chamber for a distance as great 85 as the throw of said piston, and a sleeve carried by said stem and loosely surrounding the lower end only of said tube when said piston is in depressed position, the other portion of said tube being then exposed to 90 the fluid in said chamber.

6. In a liquid dash pot the combination of a chamber, a piston therein, a liquid in which said piston moves when the dash pot is in operation, a fixed tube extending downward 95 into said chamber and having a surface exposed to the liquid contents of said chamber and forming with the walls of said chamber a pocket for said liquid contents, a piston stem extending through said tube and connected to said piston head and a sleeve carried by said stem and loosely surrounding the lower end only of said tube when said piston is in depressed position, the other portion of said tube being then exposed to the 100 fluid in said chamber bounded on one side by the stem of said piston.

In testimony whereof I have signed my 110 name, in presence of two witnesses, this 7th day of April, in the year one thousand nine hundred and thirteen.

CHARLES WALES.
